Primary Examiner — Michael A Maharajh*(74) Attorney, Agent, or Firm* — Eversheds Sutherland (US) LLP(57) **CLAIM**

We claim the ornamental design for a pacifier, as shown and described.

DESCRIPTION

FIG. 1 is a front perspective view of a pacifier showing our new design;

FIG. 2 is a rear view showing the design of FIG. 1;

FIG. 3 is a front view showing the design of FIG. 1;

FIG. 4 is a left side view showing the design of FIG. 1;

FIG. 5 is a right side view showing the design of FIG. 1;

FIG. 6 is a top view showing the design of FIGS. 1; and,

The broken lines shown in the drawings are for the purpose of illustrating portions of the pacifier which form no part of the claimed design.

1 Claim, 7 Drawing Sheets(56)
